ABSTRACT

An improved braked or snubbed joint assembly for use for supporting a grapple, clam shell or like device, is disclosed. The present braked or snubbed joint assembly includes a first member including an element defining an elongate cylindrical bore therethrough having a central axis, and first and second outwardly tapered or conical convex axial end faces. A second member having first and second arms defining a space therebetween receives the first member, and an axial pin rotatably joins the first member and the second member. The second member includes an element located in the space which has a correspondingly tapered or conical concave axial end face positioned in spaced opposed relation to the first outwardly tapered or conical convex axial end face and the second arm includes an element located in the space which has a correspondingly tapered or conical concave axial end face positioned in spaced opposed relation to the second outwardly tapered or conical convex axial end face. Frictional brake elements are disposed between the opposed axial end faces for frictionally resisting or braking relative rotation of the first and second members.

Fig. 3

BRAKED JOINT ASSEMBLY

TECHNICAL FIELD

This invention relates generally to a braked joint assembly for rotatable support of a grapple mechanism, a clam shell device or the like, and more particularly, to a braked joint assembly including a load carrying bushing or bearing arrangement and a separate frictional brake arrangement utilizing opposed outwardly tapered or conical frictional brake elements for improved operability and cost aspects.

BACKGROUND ART

Grapple mechanisms, clam shells, and the like, are commonly suspended from the free or distal ends of boom assemblies of skidders, construction machines, and the like, for carrying pulpwood, logs and other heavy loads. Typically the grapple mechanisms and other load carrying elements are suspended from the boom assembly using at least one pin joint to allow relative rotational or pivotal movement in at least one plane. Such pin joints typically include snubbers or brakes for resisting or dampening the rotational or pivotal movement to limit the possibility of damage to the machine and personnel. However, the known pin joints including snubbers or brakes have been found to suffer from various operational, maintenance and cost disadvantages.

Reference in this regard, Johnson U.S. Pat. No. 4,573,728 issued Mar. 4, 1986 which utilizes a snubbing apparatus with planar frictional elements which suffers from the operational disadvantage of requiring high compression of the assembly to provide adequate snubbing torque. Reference also McCalum U.S. Pat. No. 5,713,688 issued Feb. 3, 1998 which discloses a braked mechanical joint assembly utilizing tapered or frusto-conical sections which taper inwardly, that is, convergingly toward the center of the joint for bearing both load forces and braking torques, which has been found to be unable to withstand operational loads under heavier loading conditions.

Accordingly, the present invention is directed to overcoming one or more of the problems as set forth above.

DISCLOSURE OF THE INVENTION

In one aspect of the present invention, an improved braked or snubbed joint assembly for supporting a grapple mechanism, clam shell or like device, is disclosed. The present braked or snubbed joint assembly includes a first member including an element defining an elongate cylindrical bore therethrough having a central axis, and first and second outwardly tapered or conical convex axial end faces extending around the bore. The present joint assembly includes a second member having first and second arms defining a space therebetween receiving the first member, the first arm including an element disposed in the space having a tapered concave axial end face located in spaced opposed relation to the first tapered or conical convex axial end face of the first member and the second arm including an element disposed in the space having a tapered concave axial end face located in opposed relation to the second tapered or conical convex axial end face, the arms having holes axially aligned with the bore of the first member. The present joint assembly includes a pin extending through the axially aligned holes and the bore rotatably joining the first member and the second member. Frictional brake elements are disposed respectively between the opposed tapered axial end faces for frictionally resisting or braking relative rotation of the first and second members.

Advantages of the braked or snubbed joint assembly of the present invention includes the separate performance of the load bearing and braking or snubbing functions by the elements defining the cylindrical bore of the first member, 5 and the frictional elements, respectively. The tapered shape of the axial end faces provides a wedging effect which enables high contact forces to be generated between the tapered end faces and the brake elements for improved braking or snubbing torque. Additionally, the outwardly 10 tapered axial end surfaces of the first member enable the element defining the cylindrical bore to be relatively long so as to be capable of carrying heavy loads and to last longer. Still further, the outwardly tapered shape enables the frictional elements to have larger surface areas of engagement 15 so as to provide improved braking or snubbing and better dissipation of heat generated by the frictional contact.

BRIEF DESCRIPTION OF THE DRAWINGS

For a better understanding of the present invention, reference 20 may be made to the accompanying drawings in which:

FIG. 1 is a fragmentary side elevational view illustrating a braked joint assembly of the present invention in association 25 with a typical grapple mechanism suspended from the free end of a boom of a work machine;

FIG. 2 is a sectional view taken through the braked joint assembly of FIG. 1; and

FIG. 3 is a fragmentary sectional view of an alternative 30 braked joint assembly according to the present invention.

BEST MODE FOR CARRYING OUT THE INVENTION

Referring now to FIGS. 1 and 2 of the drawings, the 35 numeral 10 denotes a braked joint assembly constructed and operable according to the teachings of the present invention, rotatably or pivotally supporting a conventional grapple mechanism 12 from a free end of a boom 14 of a work machine 16. Work machine 16 is representative of a wide 40 variety of log skidders and other machines including a boom or other member for supporting a grapple mechanism such as mechanism 12, a clam shell, or a like device for supporting and carrying logs or other material over rough terrain such as a forest floor or the like. Here, although only one 45 braked joint assembly 10 is shown and described which allows freedom of rotational or pivotal movement of grapple mechanism 12 about one axis, it should be understood that work machines such as work machine 16 may include one or more additional braked joint assemblies for allowing 50 freedom of movement about an additional axis or axes. It should also be understood that although it is desired to provide relative rotational or pivotal movement of the grapple mechanism 12 or other load carrying device with respect to boom 14 and machine 16, it is also typically 55 desired that such movement be braked or snubbed, that is, damped to some extent, to prevent unwieldy movement of grapple mechanism 12, particularly when unloaded, such that potential damaging contact with machine 16 and injury to personnel are avoided.

Braked joint assembly 10 includes a first member 18 which is rotatably or pivotally connected to boom 14 via a pin joint 20, which can be another braked joint assembly 10, or a different pin structure. First member 18 includes a load bearing element, such as a bushing 22, which is press fit or otherwise conventionally mounted in a bore through first member 18, bushing 22 defining a cylindrical bore 24 therethrough having a central axis 26. First member 18

includes a first annular tapered convex axial end face **28** extending around one end of bore **24**, and an opposite second annular tapered convex axial end face **30** extending around an opposite end of bore **24**. Axial end faces **28** and **30** each taper outwardly, that is, each end face extends convergingly away from the center of member **18**. This enables end faces **28** and **30** to have large surface areas to provide high braking torque, and bushing **22** to be large to provide a high load bearing capability.

Joint assembly **10** includes a second member **32** which is mounted to grapple mechanism **12**, second member **32** including first and second arms **34** and **36** defining a space **38** therebetween receiving first member **18**, first arm **34** being located in spaced opposed relation to first annular tapered convex axial end face **28** of first member **18** and second arm **36** being located in spaced opposed relation to second axial end face **30**. Arms **34** and **36** include holes **40** and **42** therethrough, respectively, axially aligned with bore **24** of first member **18**.

A pin **44** extends through axially aligned holes **40** and **42** and bore **24** to allow rotation of first member **18** relative to second member **32**. Pin **44** includes a cross pin **45** cooperatively received in a transverse groove **47** in second member **32** to prevent rotation of pin **44** relative to second member **32**, and pin **44** is secured in position by a nut **46** threadedly engaged with a threaded end **48** of pin **44**.

Second member **32** includes a first retainer member **50** disposed in space **38** between first arm **34** and first axial end face **28** of first member **18**. First retainer member **50** has a bore **52** therethrough cooperatively receiving pin **44** and a correspondingly annular tapered concave axial end face **54** positioned in spaced opposed relation to axial end face **28** of first member **18**. Second member **32** includes second retainer member **56** disposed in space **38** between second arm **36** and axial end face **30** of first member **18**, second retainer member **56** including a bore **58** therethrough receiving pin **44**, and a corresponding annular tapered concave axial end face **60** positioned in spaced opposed relation to axial end face **30**. Additionally, first and second retainer members **50** and **56** each include an outwardly projecting tab **62** received in a groove **64** of second member **32** for connecting members **50** and **56** to second member **32** or other suitable structure for allowing relative axial movement thereof but limiting relative rotation thereof.

Joint assembly **10** includes an annular tapered frictional brake element **66** disposed between axial end face **28** of first member **18** and axial end face **54** of first retainer member **50**, and another annular tapered frictional brake element **68** disposed between axial end face **30** of first member **18** and axial end face **60** of second retainer member **56**. Frictional brake elements **66** and **68** are each composed of a material having a relatively high coefficient of friction and a good heat dissipation property, such as, but not limited to, a semi-metallic material such as a composite of an aramid fiber and a metal or other material, a frictional polymeric material such as sold under the tradename VESPEL available from DuPont, and metallic materials such as aluminum and zinc blends and the like. Joint assembly **10** includes an element **70** for axially biasing retainer members **50** and **56** toward first member **18** for exerting a compressive force against brake elements **66** and **68** for increasing the frictional resistance to the relative rotation thereof. Here, element **70** includes a plurality of spring members **72** which are belleville washers disposed around pin **44** between arms **34** and **36** and the respective retainer members **50** and **56**. Alternatively, other spring members could be used in element **70**, such as wave springs or the like. Element **70**

additionally includes a cylindrical sleeve **74** extending around pin **44** and extending through a hole **42** of arm **36**, sleeve **74** being axially slidable along pin **44**. Nut **46** is threadedly engageable with pin **44**, as shown, to abut and urge sleeve **74** against the adjacent spring member **72** to resiliently compress spring members **72** to urge retainer members **50** and **56** simultaneously toward first member **18**. This acts to increase the compressive pressure of engagement between brake elements **66** and **68** and the axial end faces **28**, **30**, **54** and **60**, the pressure exerted being adjustable by threaded movement of nut **46** about pin **44**.

Additionally, during use, brake elements **66** and **68** will wear resulting in the accumulation of particles of the worn frictional material in the spaces adjacent the axial ends of bushing **22**. To prevent these particles, which are abrasive by their nature, from reaching and damaging the bearing surfaces of bushing **22** and pin **44**, sealing rings **75** of elastomeric or other suitable construction are provided around pin **44** adjacent the ends of bushing **22**.

Referring to FIG. 3, joint assembly **10** is shown including an alternative element **76** for axially biasing retainer members **50** (FIG. 2) and **56** toward first member **18** for adjustably increasing or decreasing the frictional resistance to relative rotation of members **18** and **32**. Element **76** includes a grease zirc **78** communicating through a passage **80** with a grease chamber **82** in second arm **36** around pin **44**, one end of grease chamber **82** being enclosed by a cylindrical sleeve **84** extending around pin **44** in abutting relation with an axial end of second retainer member **56** modified for this purpose, chamber **82** being sealed by O-rings **85** extending around pin **44** and sleeve **84** to prevent loss of grease or other liquid under pressure within chamber **82**. Grease or other suitable liquid injected into chamber **82** through zirc **78** is operable to urge sleeve **84** into contact with retainer member **56** to apply increased pressure against brake elements **66** (FIG. 2) and **68**.

INDUSTRIAL APPLICABILITY

Utilizing either element **70** or element **76** for axially biasing retainer members **50** and **56** against brake elements **66** and **68**, the relative rotatability of first member **18** and second member **32** via retainer members **50** and **56** can be adjustably snubbed or braked as desired.

Meanwhile, the load carried by grapple mechanism **12** is transmitted from second member **32** to first member **18** directly via pin **44** and bushing **22** without involving or loading brake elements **66** and **68**, such that the load carrying and braking elements and functions are effectively separated. The load carrying bushing **22** is physically separate from the frictional brake element **66** and **68** such that heat generated by the braking or snubbing action of frictional elements **66** and **68** does not have a significant negative effect on bushing **22**. The outward tapered or conical direction of the axial end faces of first member **18** and retainer members **50** and **56** enables brake elements **66** and **68** to be large in surface area such that high braking or snubbing torque can be achieved, while bushing **22** can be made as large or small as required for carrying anticipated radial and bending moment loads. In this regard, the angular orientation of end faces **28**, **30**, **54** and **60** can be varied from the angles shown in FIGS. 2 and 3 to enable increasing or decreasing the braking or snubbing capability of joint assembly **10**, it having been found that end face angles with respect to axis **26** of between about 15 and about 45 degrees being suitable for a wide variety of applications, although other angles either larger or smaller being likewise usable.

Here, it has been found that the smaller the angle used, the greater the wedging effect or contact pressure that can be achieved by urging retainer members 50 and 56 axially toward first member 18 with a given axial force, thereby enabling high braking or snubbing torque to be achieved using smaller adjusting components such as nut 46 and sleeve 84. Use of separate brake elements and load bearing elements additionally enables replacement of one without replacement of the other to thereby provide a cost advantage.

Other aspects, objects and advantages of the present invention can be obtained from a study of the drawings, the disclosure and the appended claims.

What is claimed is:

1. A braked joint assembly, comprising:

a first member including a bushing defining an elongate cylindrical bore therethrough having a central axis, and opposite first and second outwardly tapered convex axial end faces extending around the bore;

a second member having first and second arms defining a space therebetween receiving the first member, the first arm including an element disposed in the space having a tapered concave axial end face located in opposed relation to the first outwardly tapered convex axial end face of the first member and the second arm including an element disposed in the space having a tapered concave axial end face located in opposed relation to the second outwardly tapered convex axial end face, the arms having holes axially aligned with the bore of the first member;

a pin extending through the axially aligned holes and the bore rotatably joining the first member and the second member; and

frictional brake elements disposed respectively between the opposed tapered axial end faces for frictionally resisting relative rotation of the first and second members.

2. The braked joint assembly of claim 1, wherein the elements of the first and second arms of the second member having the tapered concave axial end faces comprise retainer members, the retainer members including elements cooperatively engageable with the second member to prevent relative rotation thereof.

3. The braked joint assembly of claim 2, further comprising an element axially biasing the retainer members toward the first member including spring members disposed between the arms of the second member and the retainer members, a cylindrical sleeve extending around the pin adjacent one of the spring members and extending through the hole in one of the arms, the sleeve being axially slidable along the pin, and an element for applying an axial force against the sleeve for urging the spring members into engagement with the retainer members.

4. The braked joint assembly of claim 3, wherein the element applying the axial force against the sleeve comprises a nut threadedly mounted on the pin.

5. The braked joint assembly of claim 3, wherein the element axially biasing the retainer members toward the first member comprises a fluid.

6. The braked joint assembly of claim 3, wherein the element axially biasing the retainer members toward the first member is adjustable.

7. A braked joint assembly, comprising:

a first member including a bushing defining a cylindrical bore therethrough having a central axis, and opposite first and second outwardly tapered convex axial end faces extending around the bore;

a second member having first and second arms defining a space therebetween receiving the first member with the first arm in spaced opposed relation to the first outwardly tapered convex axial end face of the first member and the second arm in spaced opposed relation to the second outwardly tapered convex axial end face, the arms having holes axially aligned with the bore of the first member;

a pin extending through the axially aligned holes and the bore rotatably joining the first member and the second member;

a first retainer member disposed in the space between the first arm and the first tapered convex axial end face of the first member, the first retainer member having a correspondingly tapered concave axial end face positioned in spaced opposed relation to the first outwardly tapered convex axial end face, and a second retainer member disposed in the space between the second arm and the second outwardly tapered convex axial end face, the second retainer member having a correspondingly tapered concave axial end face positioned in spaced opposed relation to the second outwardly tapered convex axial end face, the first and second retainer members including elements cooperatively engageable with the second member for limiting relative axial rotation thereof;

frictional brake elements disposed respectively between the first member and the retainer members adapted for engaging the axial end faces thereof for frictionally resisting relative rotation thereof; and

an element axially biasing the retainer members toward the first member for increasing the frictional resistance to the relative rotation thereof.

8. The braked joint assembly of claim 7, wherein the element axially biasing the retainer members toward the first member comprises spring members disposed around the pin between the arms of the second member and the retainer members, a cylindrical sleeve extending around the pin adjacent one of the spring members and extending through the hole in one of the arms, the sleeve being axially slidable along the pin, and an element for applying an axial force against the sleeve for urging the spring members into engagement with the retainer members.

9. The braked joint assembly of claim 8, wherein the element applying the axial force against the sleeve comprises a nut threadedly mounted on the pin.

10. The braked joint assembly of claim 7, wherein the elements cooperatively engageable with the second member comprise tabs slidably received in axial grooves of the second member.

11. The braked joint assembly of claim 7, wherein the element axially biasing the retainer members toward the first member comprises a fluid.

12. The braked joint assembly of claim 7, wherein the element axially biasing the retainer members toward the first member are adjustable.

13. A braked joint assembly, comprising:

a first member including a bushing defining an elongate cylindrical bore therethrough having a central axis, and opposite first and second tapered convex axial end faces extending around the bore;

a second member having first and second arms defining a space therebetween receiving the first member, and members disposed between the arms and the first member having tapered concave axial end faces located in opposed relation to the first and second tapered

convex axial end faces of the first member, respectively, said arms and said members disposed between the arms and the first member having holes axially aligned with the bore of the first member; a pin extending through the axially aligned holes and the bore rotatably joining the first member and the second member; and frictional brake elements disposed respectively between the opposed axial end faces for frictionally resisting relative rotation of the first and second members.

5

14. The braked joint assembly of claim 13, wherein the members having the tapered concave axial end faces comprise retainer members connected for rotation with the second member, at least one of the retainer members being axially movable relative to the second member for applying a compressive force against the frictional brake elements.

15. The braked joint assembly of claim 13, wherein the axial end faces are oriented at between about a 15 degree angle and about a 45 degree angle to the central axis.
